DUPLICATING APPARATUS

Morris P. Neal, Villa Park, and William J. Champion, La Grange, Ill., assignors to Ditto, Incorporated, Chicago, Ill., a corporation of West Virginia

Application April 7, 1939, Serial No. 266,519

6 Claims. (Cl. 101—147)

Our invention relates to duplicating apparatus of the type in which a master sheet of aluminum or other suitable material is carried around by a drum so as to receive first a film of ink repellent which is distributed evenly over the face of the sheet, and to receive then a supply of ink, after which the master sheet is carried into impression relationship with a copy sheet.

Our invention relates particularly to the means for feeding a film of repellent to the master sheet. Our improved construction makes use of a roller having an outer face portion of absorbent material which is journaled in position to engage the master sheet as it is carried around by the drum, the repellent being fed to the roller by a ductor roll which is moved back and forth for engaging alternately the repellent applying roller and an absorbent member to which a supply of the repellent is fed. In our preferred form of apparatus, the ductor roll is formed of sponge rubber with the pores open at the outer face of the roll so as to enable the roll to absorb freely a considerable quantity of water or other suitable ink repellent material brought into contact with the roll.

In our improved arrangement a quantity of ink repellent is carried by a receptacle in which there is mounted an absorbent member which extends well into the body of the repellent. In the preferred form of the device, the absorbent member is in the form of a piece of felt, a piece of sponge rubber or a porous stone such as lava or fire brick. The amount of the repellent picked up by the ductor roll is controlled in our improved structure by an adjustment of the degree of pressure of the ductor roll on the absorbent member in the receptacle. When the compressible ductor roll is pressed firmly against the absorbent member, the ductor roll is flattened somewhat so as to cause a substantial surface contact between the roll and the absorbent member for bringing a considerable number of the pores in the roll into direct engagement with the supply of repellent carried by the absorbent member and for pressing the air from such pores for enabling the pores to be filled with the repellent by a mechanically produced suction pumping action.

It is another object of our invention to improve devices of this type in sundry details hereinafter pointed out.

The preferred means by which we have accomplished our several objects are illustrated in the accompanying drawing in which—

Fig. 1 is a diagrammatic view showing the pre-

ferred form of our apparatus in connection with a conventional form of drum;

Fig. 2 is a view similar to a portion of Fig. 1 but showing a changed position of some of the parts; and;

Figs. 3 and 4 are views similar to a portion of Fig. 1 but showing modified forms of construction.

Referring now to Figs. 1 and 2 of the drawing, in which corresponding parts are indicated by the same reference characters, 10 indicates a framework in the form of a housing of sheet metal, a fragmentary portion of which is shown in the several views, such frame having a drum 11 rotatably mounted by means of a shaft 12 thereon. In the arrangement shown, the drum 11 comprises two portions 13 and 14 of different diametrical size, the drum portion 14 having a master sheet 15 wrapped thereabout and secured thereto by any suitable mechanism not illustrated.

Upon the plate 10 adjacent to a flange 16 at one edge thereof, we have mounted a receptacle 17, such receptacle in the arrangement shown 25 being supported by a pivotally mounted plate 18 which is adjustably supported in position by means of a set screw 19 mounted in a bracket 20 in the form of a yoke carried by the flange 16. The set screw 19 is provided on its lower end with a knurled head 21 and is provided at an intermediate point with a knurled roller 22 which is engaged by a spring 23 carried by the bracket 20 serving to hold the roller 22 and the screw 19 releasably against rotary movement. The arrangement is such that when the screw 19 is given a rotary movement against the action of the spring 23, the screw is caused to move upwardly or downwardly depending upon the direction of rotation so as to give the plate 18 and the receptacle 17 a corresponding vertical movement.

Between arms 24 pivotally mounted upon the plate 10 and a corresponding frame member at the opposite side of the machine, we have rotatably mounted a roller 25 having its outside face portion formed of felt or other suitable absorbent material, such roller 25 being positioned a short distance above the receptacle 17. Stop mechanism comprising a set screw 26 is provided for limiting the movement of the arms 24 and the roller 25 toward the drum 11, springs 27 being connected between the upper ends of the arms 24 and the frame plate 10 serving normally to press the roller 25 against the master sheet 15 carried by the drum 11 as the drum rotates. The set

screw 26 serves to hold the roller 25 out of engagement with the drum section 13.

Within the receptacle 17, we have provided an absorbent member 28 which in the arrangement shown in Figs. 1 and 2 is non-yielding, being formed of lava or fire brick, or the like. The arrangement is such that the absorbent member 28 extends into direct engagement with a body of water or other suitable ink repellent 29 within the receptacle 17 so as to keep the member 28 continuously saturated with the repellent.

For taking repellent from the absorbent member 28 and applying it to the roller 25, we have provided a ductor roll 30 which in the arrangement shown is formed of sponge rubber with the pores of the rubber open at the outer face of the roll so as to make the roll readily wettable and to enable the roll to hold by absorption a considerable quantity of water or other liquid. In the arrangement shown, the ductor roll 30 is journaled between arms 31 carried by a shaft 31a journaled in the arms 24 so as to enable the ductor roll to move into engagement alternatively with the roller 25 and the absorbent member 28. A spring 32 is provided for pressing the arms 31 normally into position for holding the ductor roll 30 in engagement with the roller 25. At one side of the machine, the arm 31 is provided with a second arm 33 provided at its outer end with a roller 34 rotatably mounted thereon in position to engage cams 35 and 36 carried by the drum 11. The arrangement is such that upon each revolution of the drum the cams 35 and 36 engage the roller 34 for moving the arms 33 and 31 in clockwise direction in Figs. 1 and 2 against the action of the spring 32 for carrying the ductor roll 30 out of engagement with the roller 25 and pressing such ductor roller strongly against the absorbent member 28 in the receptacle 17 so as to flatten the ductor roll, as is clearly shown in Fig. 2. By this flattening operation, the extent of face contact of the roll 30 with the absorbent member 28 is increased, so as to control the amount of repellent taken up by the ductor roll from said member 28. The compression of the roller 30 against the absorbent member 28 not only increases the area of contact but also collapses the pores of the porous rubber of the roll 30 so as to force the air out of said pores. When the roll 30 is then retracted from engagement with the absorbent member 28, the pores expand by the resiliency of the rubber and are filled with the repellent by a mechanical pumping action by the force of suction.

In the arrangement shown, the spring means 32 serve to press the roll 30 against the roller 25, whereas said roll 30 is pressed against the absorbent member 28 by positively acting means comprising in the arrangement shown the roller 34 and the cams 35 and 36. In the construction illustrated, the cams 35 and 36 are comparatively short so as to insure that the roll 30 shall engage the roller 25 during the major portion of each revolution of the drum and that the engagement of the roll 30 with the absorbent member 28 takes place during only a minor portion of a revolution of the drum.

Whenever it is desired that the amount of repellent applied to the roller 25 be increased, this effect is brought about by an upward movement of the receptacle 17 and the absorbent member 28 by the use of the adjustable set screw 19.

In the arrangement shown in Fig. 3, the construction is similar to that above described in connection with Figs. 1 and 2, except that a

modified form of ductor roll and a modified form of absorbent member are employed. In the arrangement shown in Fig. 3, a ductor roll 37 is employed having a facing of ordinary close grained rubber with its outer face roughened so as to make it readily wettable. In this arrangement of Fig. 3, the absorbent member in the receptacle 17 is in the form of a block of sponge rubber 38 with the pores open at the top and side faces of the block.

In the arrangement shown in Fig. 4, a further modified form of absorbent member is employed. The absorbent member of the Fig. 4 arrangement is in the form of a block of packed felt 39, the arrangement in said figure being otherwise the same as that shown in Fig. 2.

We have found by the use of our improved arrangement that it is very effective for applying a very thin film evenly upon a master sheet 15 as it is carried around by the drum. When the amount of repellent is to be increased or decreased, the desired result can be obtained very readily by an adjustment of the set screw 19.

While we prefer to employ the form and arrangement of parts as shown by our drawing and as above described, it is to be understood that our invention is not limited to the arrangement shown except so far as the claims may be so limited, it being understood that changes might well be made in the form and arrangement of the parts without departing from our invention.

We claim:

1. In a moistening mechanism for applying moisture to the surface of a member carried past said mechanism, the combination of a roller rotatably mounted in position to engage said member, a receptacle for liquid extending along said roller adjacent thereto, an absorbent member in said receptacle extending downwardly into position to engage a body of liquid in the receptacle, a ductor roll having its outer face and a comparatively large portion of its body formed of resilient compressible and absorbent material rotatably mounted between said first named roller and said absorbent member and movable into position to engage the roller and the absorbent member alternatively for taking liquid from said absorbent member and feeding it to said roller, and means for giving said ductor roll reciprocating movements between said first-named absorbent member and said first-named roller adapted to flatten said ductor roll substantially against the absorbent member in the receptacle in position to take up by suction a substantial supply of liquid from said absorbent member for application to said roller.

2. In a moistening mechanism for applying moisture to the surface of a member carried past said mechanism, the combination of a roller rotatably mounted in position to engage said member, a receptacle for liquid extending along said roller adjacent thereto, a substantially rigid porous absorbent member in said receptacle extending downwardly into position to engage a body of liquid in the receptacle, a ductor roll having its outer face and a comparatively large portion of its body formed of resilient compressible and absorbent material rotatably mounted between said first named roller and said absorbent member and movable into position to engage the roller and the absorbent member alternatively for taking liquid from said absorbent member and feeding it to said roller, means for giving said ductor roll reciprocatory movements between said absorbent member and

said first-named roller, and adjustable means for varying the pressure of said ductor roll on said absorbent member for controlling the amount of liquid taken up by the ductor roll for application to said first-named roller.

3. A mechanism for applying moisture to a member moving past said mechanism, comprising in combination a roller having a facing portion of absorbent material rotatably mounted in position to engage said member as it is carried along, a receptacle for liquid extending along said roller adjacent thereto, an absorbent member in said receptacle extending downwardly into position to engage a body of liquid in said receptacle, a ductor roll of resilient yielding material comparatively much more readily compressible than said absorbent member having a readily wettable outer face and rotatably mounted between said first named roller and said absorbent member and movable into position to engage the roller and the absorbent member alternatively for taking liquid from said absorbent member and feeding it to said roller, means for moving said ductor roll into engagement alternately with said roller and said absorbent member and means for adjusting said receptacle and the absorbent member therein toward and from said first-named roller for varying the degree of flattening of said ductor roll and thus controlling the amount of liquid fed to said roller.

4. A mechanism for applying moisture to a member moving past said mechanism, comprising in combination a roller rotatably mounted in position to engage said member as it is carried along, a receptacle for liquid extending along said roller adjacent thereto, an absorbent member formed of porous stone in said receptacle extending downwardly into position to engage a body of liquid in said receptacle, a ductor roll having its outer face and a comparatively large portion of its body formed of resilient compressible and absorbent material rotatably mounted between said first named roller and said absorbent member and movable into position to engage the roller and the absorbent member alternatively for taking liquid from said absorbent member and feeding it to said roller, and means

for moving said ductor roll into engagement alternately with said roller and said absorbent member.

5. A mechanism for applying moisture to a member moving past said mechanism, comprising in combination a roller rotatably mounted in position to engage said member as it is carried along, a receptacle for liquid extending along said roller adjacent thereto, an absorbent member in said receptacle extending downwardly into position to engage a body of liquid in said receptacle, a ductor roll of resilient yielding material comparatively much more readily compressible than said absorbent member and having an absorbent outer face and rotatably mounted between said first named roller and said absorbent member and movable into position to engage the roller and the absorbent member alternatively for taking liquid from said absorbent member and feeding it to said roller, means for moving said ductor roll into engagement alternately with said roller and said absorbent member, and adjustable means for varying the degree of pressure of said ductor roll on said absorbent member for controlling the amount of liquid taken up by said ductor roll.

6. A mechanism for applying moisture to a member movable past said mechanism, comprising in combination a roller rotatably mounted in position to engage said member as it is carried along, a receptacle for liquid extending along said roller adjacent thereto, an absorbent member formed of packed felt non-rotatably mounted in said receptacle and extending downwardly into position to engage a body of liquid in said receptacle, a ductor roll having its outer face and a comparatively large portion of its body formed of resilient compressible and absorbent material rotatably mounted between said first-named roller and said absorbent member and movable into position to engage the roller and the absorbent member alternatively for taking liquid from said absorbent member and feeding it to said roller, and means for moving said ductor roll into engagement alternately with said roller and said absorbent member.
